(57) **CLAIM**

The ornamental design for a converter, as shown and described.

DESCRIPTION

FIG. 1 is a perspective view of the converter of the present invention;

FIG. 2 is a front view of the converter of the present invention;

FIG. 3 is a back view of the converter of the present invention;

FIG. 4 is a left side view of the converter of the present invention;

FIG. 5 is a right side view of the converter of the present invention;

FIG. 6 is a top view of the converter of the present invention; and,

FIG. 7 is a bottom view of the converter of the present invention.

The components shown with broken lines do not make up a part of the claimed design.

1 Claim, 5 Drawing Sheets

FIG. 2

FIG. 3

FIG. 4

FIG. 5

FIG. 6

FIG. 7

Disclaimer and Dedication

D. 490,785 S — Jeffrey John Boylan, Richardson, TX (US); Timothy Richard Fellows, Mesquite, TX (US); Randy Thomas Heinrich, Rockwall, TX (US); Gary Robert Kidwell, Plano, TX (US); Victor Ke-Ji Lee, Plano, TX (US). CONVERTER. Patent dated June 1, 2004. Disclaimer filed September 23, 2015, by the assignee, TDK-Lambda Corporation.

Hereby disclaims and dedicates to the Public, the remaining term of said design patent.
